UNITED STATES PATENT OFFICE.

JAMES J. DAVIS, OF PITTSBURGH, PENNSYLVANIA, ASSIGNOR TO THE LOYAL ORDER
OF MOOSE, OF MOOSEHEART, ILLINOIS.

DESIGN FOR AN EMBLEMATIC CAP.

Application filed February 8, 1928. Serial No. 25,259. Term of patent 14 years.

To all whom it may concern:

Be it known that I, JAMES J. DAVIS, a citizen of the United States, residing at Pittsburgh, in the county of Allegheny and State of Pennsylvania, have invented a new, original, and ornamental Design for an Emblematic Cap, of which the following is a specification, reference being had to the accompanying drawing, forming part thereof.

The figure is a perspective view of an emblematic cap, showing my new design.

I claim:

The ornamental design for an emblematic cap, as shown.

JAMES J. DAVIS.
